UNITED STATES PATENT OFFICE.

WALTER P. OSGOOD, OF MALDEN, WILLIAM E. SMITH, OF LYNN, AND JOEL U. PEABODY, OF SWAMPSOFT, MASSACHUSETTS, ASSIGNEES TO BOSTON MACHINE WORKS COMPANY, OF LYNN, MASSACHUSETTS, A CORPORATION OF MASSACHUSETTS.

CEMENTING MACHINE.

Application filed January 14, 1919. Serial No. 271,084.

To all whom it may concern:

Be it known that we, WALTER P. OSGOOD, WILLIAM E. SMITH, and JOEL U. PEABODY, citizens of the United States, and residents, respectively, of Malden, in the county of Middlesex, of Lynn, in the county of Essex, and of Swampscoft, in the county of Essex, and Commonwealth of Massachusetts, have invented an Improvement in Cementing Machines, of which the following description, in connection with the accompanying drawings, is a specification, like characters on the drawings representing like parts in each of the several views.

15 This invention relates to cementing machines and more particularly to the type employed in the manufacture of boots and shoes for applying cement uniformly to marginal portions of leather or other material such for instance as vamps. A principal object of the invention is to provide an improved means whereby the material piece such as a shoe vamp is protected and guarded from daubing or smearing with cement on 20 any portion of the surface thereof except the edge to be cemented. To this end one feature of the invention consists in the provision of improved means for clearing the work from the applying roll and from the adjacent table surface as soon as it passes the cementing point while another feature consists in improved means for cleaning effectively the backing roll which co-operates with the applying roll of any cement that it may pick up in its operating function. A still further feature consists in an improved construction of cement gauge or scraper that is combined with and borne by an adjustable work table. A further feature relates to an improved construction of work gauge and guide adapted to be located at the end of an extended horn or neck in which the applying roll is mounted, and operative to guide and direct a work piece being operated on such as a closed 35 vamp away from the machine as fast as it is cemented, thus further preventing daubing or smearing. Another object is to provide means associated with the carrier of the backing roll adapted to be set optionally for holding said roll normally pressed toward the applying roll or away therefrom. The foregoing and other objects and advantages of the invention will more fully appear from

the following detailed description, and the distinctive features of novelty will be pointed out in the appended claims.

Referring to the drawings:

Fig. 1 is a side elevation of a machine embodying the invention;

Fig. 2 is a vertical lengthwise section thereof looking from the side opposite to that of Fig. 1;

Fig. 3 is a transverse vertical section on line 3—3 of Fig. 2;

Fig. 4 is a partial plan view of the rear portion of the machine showing the mounting of the overhanging arm;

Fig. 5 is an enlarged partial front end view of the machine, the lower part of the housing being broken away;

Fig. 6 is an enlarged partial plan view showing the horn in which the applying roll is mounted; and

Fig. 7 is an enlarged sectional detail on line 7—7 of Fig. 1.

10 indicates the machine frame, the interior of which is hollow to constitute a cement reservoir 11, the top of which is normally closed by a cover 12 hinged at one side to the machine housing at 13 and adapted to be secured at its other side by swinging nut clamps 14. In the top of the machine frame adjacent its opposite ends are provided spaced apart bearings 15 in which is journaled a shaft 16 having fixed on a projecting rear end thereof driving pulleys 17, one of these being fast to serve as a driving pulley and the other being loose as usual. The forward end of the shaft 16 projects into an elongated horn or neck 18 secured to the top 20 of the machine frame at the front end thereof either by threading thereinto with a securing screw 19 as shown or otherwise as may be preferred. The extremity of the shaft 16 within the horn 18 has fixed thereto a cement applying roll 20 suitably grooved peripherally and lengthwise thereof as usual, this roll thus occupying the outer end portion of the horn 18 and projecting up through the top thereof to present an exposed cement applying edge. This cement applying edge projects through a work table 21 slidably fitted to transverse undercut ways 22 in a flattened top surface 23 on the outer portion of the horn, the outer one of 25 these ways being constituted by a removable

end cap 24 forming a detachable end closure for the horn 18. In accordance with our invention the table 21 extends at one side of the horn with a downturned projection 21^a 5 to which is swiveled as seen at 25 an adjusting screw 26 with a knurled operating head 26^a which is threaded into the metal of the horn. In accordance with our invention the work table 21 itself is made to constitute a 10 cement scraper and gauge, for this purpose having a formed edge 27 adapted to be adjusted against or into proximity to the periphery of the applying roll by means of the screw 26. We consider this gauging of 15 the cement at the table as being a valuable feature of invention since with the cement gauge spaced away from and below the table the cement can crawl over the gauge and flow again on to the roll more or less thereby 20 losing control of the cement. It is to be noted that the provision of the screw 26 swiveled to the table permits the use of an adjusting screw working parallel to the table face and thus to best advantage as will 25 be understood. For supplying cement constantly to the horn 18 suitable means shown as a screw conveyer 28 is provided working in a tubular way 29 in the bottom of the reservoir, this screw having its shank journaled and swiveled at 30 in the machine base and having drive connection through a gear 31 from the prime drive shaft 16. The 30 operation of this screw delivers the cement to a vertical passageway 32 closed off at the 35 front of the machine by means of a transverse barrier 33, the upper part of this barrier being constituted by a gate 33^a adapted to be adjustably clamped by means of a bolt and slot connection 34 to the lower barrier 40 portion whereby a spillway indicated at 35 and adjustable in extent is provided at the top of the reservoir, the adjustment of this spillway permitting a proper delivery of cement to the horn 18 to be insured without an 45 excess delivery thereto which would cause the cement to ooze up past the applying roll, such adjustment being desirable on account of varying degrees of thickness and viscosity in different kinds of cement. For 50 co-operation with the applying roll 20 a backing and presser roll or disc 36 is provided, this roll being positively driven in unison with the applying roll and thus co-operative therewith also as a feed roll for 55 advancing the material. The backing roll 36 is fixed at the outer extremity of a shaft 37 journaled in bearings 38, 39 at the inner and outer extremities respectively of an 60 overhanging arm 40 pivoted at 41 to the rear of the machine frame in bearing brackets 42 that may be formed on and extend up from the cover 12. The arm 40 is adjustably limited as to its downward movement by an adjustable screw bolt 43 threaded 65 therethrough and adapted to impinge on the

machine top to thus determine the downward movement of the roll 36 while a stop 44 set into a lug at the rear of the arm engages a fixed lug on the machine frame to limit the upward movement thereof. The 70 shaft 37 is driven constantly in unison with the shaft 16 by a pinion 45 meshing with the gear 31 on the shaft 16. For operating the swinging arm 40, it is engaged by the outer extremity of an arm 46 loosely mounted on the pivot pin 41 and having rigid therewith another arm 47 which may be connected to a suitable treadle (not shown). For tensioning the arm 40 a leaf spring 48 is provided this spring being anchored at one end to a disc 49 clamped for angular adjustment on an 80 outer extension of the pin 41 by means of clamp screws 50. The free end of this spring engages a pin 51 carried by the arm 47. The purpose of this construction is to provide 85 for setting the spring so as to tension the arm 40 either for upward or downward swinging according to the kind of work in hand. Thus for operating on closed vamps the arm should be tensioned to swing normally upward while for open vamps and with continuous feed work the arm should be tensioned to swing downwardly. The 90 change from one setting to the other by the present construction is attained by loosening the set screws 50 and turning the disc 49 on the shaft 41 either to the left as seen in Fig. 1 for tensioning the arm upward or to the right for tensioning the same downward. For clearing and cleaning the backing roll 100 36 of any cement that may be gathered up thereby, a scraper or clearer plate 51 is provided fixed at the lower side of a hollow head 52 carried by an arm 53, said arm being mounted on a pin 54 socketed in and projecting from the forward end of the arm 40 to which it is clamped by a screw 55. The arm 53 is mounted to turn on the pin 54 and it is tensioned by a coil spring 56 mounted on the pin 54 one end of said spring engaging the arm 53 while its other end is anchored to a collar 57 angularly adjustable on the pin 54 so that the tensioning of the arm 53 may be varied. The hollow passage 110 52^a in the head 52 communicates with a flexible return tube 58, one end of which is carried by the head 52 and the other end of which empties down into the reservoir through the cover 12. This discharge end of said tube as seen at 59 is above and adjacent to the shaft 16 wherefrom it results that the viscous cement will be wound on to the shaft 16 and thus drawn out through the tube 59 in this way facilitating the return movement of the cement. It is desirable that 115 the cement on its return course as well as the body of cement in the reservoir be kept from contact with the air and as far as possible and for this purpose as well as to facilitate the 120 return cement movement we provide an ad- 125 130

justable gate formed as an arcuate plate 60 clamped to the head 52 by an elongated slot and screw 61, this gate extending down to cover more or less an opening 52^b which extends out from the opening 52^a opposite the roll 36. The head 52 is formed with an outer retaining flange 52^c at this point whereby a shallow pocket is formed in which a quantity of cement as gathered by the roll 36 and cleared as described will accumulate in operation, and the adjustment of the gate 60 may be made such that for any particular kind of cement there will be just enough accumulation to seal the opening into the passage 52^a without an excess accumulation sufficient to overflow, thus keeping the return passage sealed and making the cement return more uniform and effective. The clearer or scraper plate 51 which is held in operative relation to the roll 36 by the spring 56 keeps the roll 36 substantially cleaned and cleared of cement but to further clean this roll so that it will not even in the slightest degree soil the incoming material, we preferably provide a secondary wiper or cleaner member formed as a box or holder 62 in which textile waste or like cleaning material may be carried, this box being held pressed forward so that its wiping contents engage the roll, by a spring plate 63, which serves as its mounting and is itself adjustably clamped as seen at 64 to the forward end of the arm 40. This wiper box which is located just below the scraper plate 51 is thus adapted to complete cleaning of the roll 36 just before it engages the incoming material.

In accordance with our invention the horn 18 over the table 21 is equipped with a wire 40 65 bowed a little distance from the table and extending thereacross adjacent the delivery side of the applying roll 20 and also with another wire 66 adjustably clamped as seen at 67 to the side of the horn and extending transversely of the axis thereof inward and also bowed in so that its extremity engages in an intermediate groove of the applying roll as seen at 68. The purpose of the wire 65 is to break and remove the cement tending to cling between the two rolls while the transverse wire 66 prevents the material piece being doubled up by the movement of the wheels or becoming clogged between the table edge and the roll, i. e., this cross wire 66 is in the nature of a work clearer and its point extends down into the roll so as to prevent the cement from flowing therewith. We also preferably provide a flange piece 69 at the outer extremity of the horn presenting a gradually inclined edge 69^a to the material piece in the direction of feed, the purpose of this being to guard the cemented edge and keep it from coming prematurely into contact with any foreign material which would adhere thereto. When the

machine is to be used for operating on closed vamps we provide a special form of a work gauge indicated at 70 this being adjustably clamped to the end of the horn by a screw and slot 71 and having an inclined work gauging and guiding edge 72 extending over the applying roll and a gauge wall 73 alined with the outer edge of the applying roll. In operating on closed vamp pieces this gauge may be set so as to carry the work as fast as cemented away from the machine preventing daubing and also serving to hold the work from being pulled out accidentally. This provision of an outside work gauge in conjunction with the secondary roll cleaner 62 serves to keep the vamp exceptionally clean and free from soiling with cement, the gauge acting to prevent the vamp from being soiled by contact with the machine or the rolls while the secondary cleaner insures that the pressing edge of the backing roll 36 as it revolves will have no cement adherent thereto to foul the vamp. We are aware that the invention may be embodied in other specific forms without departing from the spirit or essential attributes thereof, and we therefore desire the present embodiment to be considered in all respects as illustrative and not restrictive, reference being had to the appended claims rather than to the foregoing description to indicate the scope of the invention.

Having described our invention, what we claim as new and desire to secure by Letters Patent is:

1. A cementing machine, comprising a cement chamber having an applying roll associated therewith, a movably mounted backing roll co-operative with said applying roll, a cement return chamber associated with said backing roll and equipped with a clearer for removing cement from said backing roll, and a secondary cleaning device associated with said backing roll consisting in a wiper box.

2. A cementing machine, comprising a cement chamber having an applying roll associated therewith, a movably mounted backing roll co-operative with said applying roll, cement clearing means for said backing roll equipped with a cement return conduit, and a spring mounted secondary cleaner for said backing roll formed as a holder of waste or the like.

3. A cementing machine, comprising a cement chamber equipped with an applying roll, a movably mounted backing roll co-operative therewith, and relatively stationary means extending generally parallel to the axis of said applying roll adjacent the delivery side thereof and relatively close to the bite of said rolls for breaking up cement tending to cling between said rolls.

4. A cementing machine, comprising a cement reservoir equipped with a cement

chamber receiving cement therefrom and formed as an extended horn over which a closed shoe vamp may be fitted, an applying roll mounted in said horn, a backing roll co-operative therewith, and a work gauge mounted at the outer end of said horn and outside of said applying roll.

5. A cementing machine, comprising a cement reservoir equipped with an extended horn adapted to receive cement therefrom, an applying roll mounted in said horn, and a work gauge adjustably mounted at the extremity of said horn adapted to co-operate with said roll in cementing closed vamps or the like to carry the work away from the machine as fast as cemented.

10. A cementing machine, comprising a cement reservoir equipped with an extended horn, an applying roll mounted in said horn, a work gauge mounted at the outer extremity of said horn outside of said roll, a backing roll movably mounted to co-operate with said applying roll, a primary clearer for said backing roll equipped with 20 means for returning cement to said reservoir, and a secondary cleaner therefor consisting in a wiper device.

15. A cementing machine, comprising a cement chamber having a work table adjustably fitted at the top thereof, and an applying roll mounted in said chamber with an edge projecting up through said table, said table having an edge portion formed and adjustable therewith, adapted 30 to constitute a cement gauge for said roll.

20. A cementing machine, comprising a cement chamber having a table adjustably fitted in the top thereof, said table having an opening therein with a gauge edge formed adjustable therewith, at one side of

said opening, and an applying roll mounted in said chamber with a portion thereof fitting upward through said opening, and in co-operative relation with said gauge edge to determine the supply of cement.

25. A cementing machine, comprising a cement chamber, a work table adjustably fitted in the top thereof, an adjusting screw mounted in parallelism with said table and operatively engaging the same, and an applying roll fitted to extend up through an opening in said table, said table presenting a gauge edge adjustable therewith and co-operating with said applying roll to determine the supply of cement by said roll.

30. A cementing machine, comprising a cement chamber, a work table adjustably fitted in the top thereof, an adjusting screw mounted in parallelism with said table and operatively engaging the same, and an applying roll fitted to extend up through an opening in said table, said table at one 40 edge of said opening presenting a gauge edge adapted to be adjusted by said screw to determine the amount of cement supplied by said roll.

35. A cementing machine, comprising a cement chamber, an applying roll mounted therein, a backing roll co-operative with said applying roll, a swinging arm serving as a mounting for said backing roll, and a spring for tensioning said arm having an adjustable anchorage whereby it may be set to tension said arm to swing either upward or downward at will for the purpose stated.

40. In testimony whereof, we have signed our names to this specification.

WALTER P. OSGOOD
WM. E. SMITH
JOEL U. PEABODY.
